UNITED STATES PATENT OFFICE.

CHARLES LIONEL MARCUS AND JOSEPH A. FIELDS, OF NEW YORK, N. Y.

DESIGN FOR A COMBINED PERFUME BOTTLE AND HOLDER.

Application filed December 12, 1924. Serial No. 11,685. Term of patent 7 years.

To all whom it may concern:

Be it known that CHARLES LIONEL MARCUS and JOSEPH A. FIELDS, citizens of the United States, and residents of the city of New York, in the county of New York and State of New York, have invented a new, original, and ornamental Design for Combined Perfume Bottle and Holder, of which the following is a specification, reference being had to the accompanying drawing, forming part thereof, in which,

The figure is a perspective view showing a combined perfume bottle and holder embodying our new design which is manufactured and sold as a single unitary article.

We claim:

The ornamental design for a combined perfume bottle and holder as shown and described.

Dated New York city, Nov. 24th, 1924.

CHARLES LIONEL MARCUS.
JOSEPH A. FIELDS.
